UNITED STATES PATENT OFFICE.

HENRY L. FERRIS, OF HARVARD, ILLINOIS, ASSIGNOR TO HUNT, HELM & FERRIS.

HAY-CARRIER.

SPECIFICATION forming part of Letters Patent No. 399,140, dated March 5, 1889.

Application filed October 10, 1888. Serial No. 287,756. (No model.)

To all whom it may concern:

Be it known that I, HENRY L. FERRIS, a resident of Harvard, in the county of McHenry and State of Illinois, have invented certain new and useful Improvements in Hay-Carriers; and I do hereby declare the following to be a full, clear, and exact description of the invention, such as will enable others skilled in the art to which it pertains to make and use the same.

The object of this invention is to provide a carrier that, while acting in other respects like ordinary carriers, shall automatically adjust its wheels, so that all may at all times bear upon the supporting-track, whether or not the track is in perfect alignment.

In the drawings, Figure 1 is a side view of the carrier. Fig. 2 shows the same seen from above. Fig. 3 is a section on the line *xy*, Fig. 1. Fig. 4 shows the inside face of the side seen in Fig. 1. Figs. 5 and 6 show a slight modification, as hereinafter explained.

In the drawings, *A A'* are halves of a carrier-frame, and *B B'* are rigid arms extending upward from the parts *A A'*, respectively, and bearing at their respective extremities the four wheels *C C' C'' C'''*, mounted upon suitable gudgeons and resting upon the double track *D D'*, of ordinary construction. The arms *B'* are formed integrally with the half *A'* of the frame, as usual; but the arms *B* are formed integrally in a separate piece, and this is pivoted at its middle to the half *A* by a rivet or bolt, *E*, near its upper edge. A flange, *f*, upon the part *A* limits the oscillation of the arm upon this pivot, and a hook, *G*, engaging a flange, *H*, upon the arm's lower edge, holds the latter firmly against the outer face of the frame. As an additional security, a lip, *I*, Fig. 4, projects over the inner face of the part *A* at the pivotal point, and thus the edge of the part *A* is held and pivoted between two integrally-formed plane parallel parts of the arm, and the two wheels borne by that arm oscillate freely in a vertical plane, while they are practically held as rigidly in that plane as if formed integrally with the part *A* in the usual manner.

The two parts *A A'* inclose and support the

usual devices, (not shown,) and are bolted or riveted together in the ordinary manner.

The operation of the device is evident from the construction. The slight oscillation of the integrally-formed arms *B B'*, as the loaded carrier passes along imperfectly-adjusted sections of the track, compensates for every possible slight irregularity in the surface over which the wheels pass, and consequently the four wheels at all times bear upon the track, and thus the insecurity and strain resulting from supporting the load upon three wheels only is entirely avoided.

As it is evident that the exact construction shown need not be followed in securing adjustability of two of the wheels, I do not wish to limit myself to this precise form of embodiment of my invention.

In Figs. 5 and 6, which correspond to Figs. 1 and 3, the arms *B B'* are pivoted upon the face of the part *A* by a bolt near the upper edge thereof, and the lower edge is held by a projection, *O*, formed integrally with the arms and passing through a segmental annular aperture, *P*, in the part *A*, and thence downward a short distance in contact with the plane face thereof.

What I claim is—

1. In a hay-carrier, a carrier-frame provided with wheels adapted to engage or rest upon opposite sides of the supporting-track, the wheels of one side being mounted upon arms pivoted to said frame, substantially as set forth.

2. The combination, with the two-part carrier-frame *A A'*, having integrally-formed arms on part *A'*, said arms bearing supporting-wheels *C'' C'''*, of the integrally-formed arms *B*, pivoted on the part *A* of said frame and bearing the wheels *C C'*, substantially as set forth.

3. The combination, with the two-part carrier-frame *A A'*, one part of which is provided with integrally-formed wheel-bearing arms *B'*, of the integrally-formed arms *B*, pivoted to the other part of said frame, said arms *B* having the flange *H* and said frame part *A* having the hook *G*, adapted to engage said flange, substantially as and for the purpose set forth.

4. The combination, with the frame A A', provided with wheel-bearing arms B', formed integrally with the part A', of arms B, formed integrally with each other and pivoted to the part
5 A, and wheels C C', mounted upon the arms B, respectively, said arms B having the flange H and the lip I, and said frame part A having the hook G, adapted to engage said flange, substantially as and for the purpose set forth.

In testimony whereof I have signed this 10 specification in the presence of two subscribing witnesses.

HENRY L. FERRIS.
